(57) **CLAIM**

The ornamental design for a wire nut wrench, as shown and described.

DESCRIPTION

FIG. 1 is a front elevational view of the wire nut wrench of the present invention;

FIG. 2 is a rear elevational view of the wire nut wrench of FIG. 1;

FIG. 3 is a left side elevational view of the wire nut wrench of FIG. 1, the right view being a mirror image thereof;

FIG. 4 is a top plan view of the wire nut wrench of FIG. 1, the bottom view being a mirror image thereof; and,

FIG. 5 is an enlarged cross-sectional view taken along line 5—5 of FIG. 4.
